UNITED STATES PATENT OFFICE

91,100

DESIGN FOR A LAMP GLOBE

George H. Cole, Milwaukee, Wis., assignor to
Line Material Company, South Milwaukee,
Wis.

Application September 3, 1932. Serial No. 44,751

Term of patent 14 years

To all whom it may concern:

Be it known that I, GEORGE H. COLE, a citizen of the United States, residing at Milwaukee, in the county of Milwaukee and State of Wisconsin, have invented a new, original, and ornamental Design for Lamp Globes, of which the following is a specification, reference being had to the accompanying drawing, forming part thereof.

In the accompanying drawing, Figure 1 is a side elevation of my ornamental lamp globe.

Figure 2 is a bottom view of the globe.

Figure 3 is a sectional view thereof.

Figure 4 is a face view of a fragment of the globe drawn to an enlarged scale.

Figure 5 is a perspective view of a fragment of the globe drawn to a still larger scale.

It is to be understood that the globe is preferably formed of translucent or light transmitting material.

I claim:

The ornamental design for a lamp globe as shown and described.

In witness whereof, I have hereunto set my hand this 23rd day of August, 1932.

GEORGE H. COLE.
